(57) **CLAIM**

The ornamental design for a changing pad cover, as shown and described.

DESCRIPTION

FIG. 1 is a perspective view of a changing pad cover showing our new design;

FIG. 2 is a front view thereof, the back view being identical; FIG. 3 is a right side view thereof, the left side view being identical;

FIG. 4 is a top view thereof; and,

FIG. 5 is a bottom view thereof.

The broken lines illustrating portions of the changing pad cover form no part of the claimed design. The surface of the interior panel of material has a smooth, wipeable surface as depicted by the stipple shading. The surfaces of the exterior panels of material have a plush surface as depicted by the cross-hatch shading.

1 Claim, 2 Drawing Sheets
